UNITED STATES PATENT OFFICE.

JAMES S. PATTEN, OF BALTIMORE, MARYLAND, ASSIGNOR TO THE PATTEN SELF-OILING AXLE AND JOURNAL COMPANY OF BALTIMORE CITY.

CAR-AXLE LUBRICATOR.

SPECIFICATION forming part of Letters Patent No. 557,871, dated April 7, 1896.

Application filed July 1, 1895. Serial No. 554,617. (No model.)

To all whom it may concern:

Be it known that I, JAMES S. PATTEN, of Baltimore city, in the State of Maryland, have invented a new and useful Improvement in 5 Car-Axle Lubricators, of which the following is a specification.

This invention is in the class of axle-lubricators having a lubricant-holder containing means for taking up a liquid or semiliquid 10 lubricant and transferring it to the journal.

The means which my experience has demonstrated to be superior for this purpose are rollers mounted to rotate in a frame swiveled on the bottom of the lubricant-holder, which 15 is supported by a spring, so that they (the rollers) are held in easy-working contact with the axle-journal.

To confine the lubricant and prevent its waste, also to exclude dust, &c., I have devised and successfully used a device which 20 also serves as a "brass" or journal-bearing proper.

Practical use has demonstrated that the lubricant tends to run along the journal and thus escape at the rear end of the box. To prevent this, many expedients have been devised and tested. I have discovered a simple and effective means, which involve no supplemental device or attachment of the oil- 25 box or brass, but form integral portions of the latter, whereby important practical advantages are attained.

An important feature in the construction of the brass or bearing proper is the form of 30 its end portions, whereby the adjacent axle-journal shoulder and head are prevented from wearing recesses in the same, so that excessive friction and the consequent danger of a hot box from such cause are avoided.

40 I will proceed to describe my invention by reference to accompanying drawings, two sheets, in which—

Figure 1 is a central longitudinal section of a car-axle box, journal-bearing or brass, and 45 a lubricant-holder or oil-box, some parts being shown in dotted lines for sake of clearer illustration of more important ones. Fig. 2 is a perspective view of my improved brass or journal-bearing. Fig. 2^a is a longitudinal 50 section of an ordinary brass having its ends constructed according to my invention. Fig.

3 is a vertical cross-section of the brass and axle-journal on line xx of Fig. 1. Fig. 4 is partly an end view and partly a vertical section of the brass and journal, the section being taken just back of the flange or head of the journal. 55

Referring, in the first instance, particularly to Fig. 1, A indicates the brass or combined journal bearing and cap, which chiefly embodies my present invention. It is shown applied to an axle-journal B in connection with a lubricant-holder or oil-box C, containing oil-transfer rollers D, and is supported by a curved plate-spring E, all said parts being inclosed in an axle-box F of the pattern commonly used on railway-cars at the present time. 60

The brass and journal-cap A (shown detached and enlarged in Fig. 2) has a semi-octagonal top, pendent outwardly-curved side wings a, and a closed front end a', all constructed integrally. 65

The lower edges, Fig. 1, of such wings a and end portion or cap a' enter and lie within 70 the oil-box C. An opening a² and notch a³, formed in the end a' of the brass, are normally closed by a spring-plate a⁴, Fig. 1, that may be easily pushed back when it is desired to inspect the oil-box C or introduce a supply of 75 lubricant. The latter, being taken up by the rollers D, is constantly fed to the friction or contact surfaces of the brass A and journal B. Portions of the brass A (which is in such frictional contact and conforms thereto) 80 terminate at the sides in shoulders 1, Figs. 1, 3, and 4, that extend longitudinally of the brass. 85

A portion of the lubricant transferred to the journal is arrested by such shoulders 1 and 90 for the most part flows down the wings a and returns into the oil-box C; but a smaller portion tends to flow or "creep" along the wings a, and if unobstructed would reach and pass over the journal-shoulder 3, Fig. 1, and thus 95 escape and be wasted.

I have found that separate or independent devices for arresting this passage of the lubricant or oil, and thus confining it within proper limits, may be dispensed with and the service 100 effectively performed by means which constitute an integral portion of the brass. The

said means are most clearly represented in Figs. 1 and 2, and consist of guards 4, in the nature of ribs or projections, on the interior of the diverging wings *a* of the brass A. The 5 said ribs 4 are located at the rear end of the brass and extend downward from the semi-circular portion 1 of the same, being thus in frictional contact with the journal B at their upper ends. There may be one or more of 10 these guards 4, but I preferably employ three, one of them being at the extremity of a wing *a* and the others parallel thereto, but separated by narrow spaces.

The guards 4 not only arrest or cut off the 15 flow of oil along the inner surface of the wings *a* of the brass and divert it downward, and thus cause it to return into the oil-box C, so that escape and waste of the same at that point are avoided, but they materially brace 20 or strengthen the wings *a* where they are weakest and enable the latter to be cast very thin.

A further improvement is embodied in another integral construction of the brass, which 25 will now be described.

As usually constructed, the shoulder 3 and flange or head 3' of the axle-journal B gradually wear into the ends of the brass A, so that the latter in time comes to have recesses and 30 project over the said shoulder and flange. The frictional or wearing surface is thus increased and the danger of a hot box correspondingly so.

I so construct the ends of the brass as to 35 avoid this result at any stage in its use and wear—that is to say, I cut away the end of the brass on the upper side upon a curve or incline, as shown in Figs. 1 and 2^a. In the latter an ordinary brass is shown with its 40 ends cut back on the upper side, such cut-away portion being inclined downward to the extremities that abut the journal-shoulder and head when the brass is in use. For convenience of further description I will designate these cut-away or reduced portions as 45 "bevels."

In Fig. 1 (see also Fig. 2) the cap and bearing are shown provided with a groove 5 in each end. It will be seen that this construction is in effect the same as that shown in 50 Fig. 2^a, since the extremities of the bearing which are contiguous to or abut the ground shoulder 3 and head 3' are inclined or beveled in the same manner. In both cases such 55 extremities are intended to be of practically the same radial thickness as the ordinary shoulder and flange; but it is obvious that if the extremity of the brass be of due thickness to enable it to properly resist wear the 60 shoulder of the axle might considerably exceed it in height without any material difference in result. It will now be seen that as the extremities of the brass wear away no rabbet, recess, or overhang will be formed in 65 its extremity by contact and friction with the axle shoulder and head, despite the fact that the thickness of the beveled portion increases

from the extremities inward, since the under side of the brass A, that rests on the journal B, wears away to an extent corresponding 70 to the wear of such extremity of the bevel. Thus, practically, the beveled portions remain always of substantially the same thickness at their extremities so long as the brass is in use, and hence friction is not increased 75 by wear.

The oil which works up and obtains access to the groove 5 will flow down and out at each 80 end of the same, and thus be returned into the box C; but to permit this to be done most effectively the ends of the wings or sides *a* of the brass A are cut back, as shown at 6 in Fig. 2, so that the oil may drop free from the ends of the groove without striking upon the wings. This feature of my invention is 85 applicable to the ordinary brass or bearing, as shown in Fig. 2^a, in which the ends of such brass are shown cut away on the upper side, so that as the reduced portions in contact with the shoulder and flange of an axle-journal 90 wear back no angular recess will be formed in the ends of the brass and no increased friction or danger of a hot box will result.

By the construction before described I provide in one integral device a brass or journal-bearing proper, a journal-cap or hood-like cover and protector, and means for deflecting and confining within required limits the oil which would otherwise escape by being thrown from the axle or by passing along the 100 upper side of the journal.

My invention is not necessarily restricted to car-axles, since it is, in part at least, applicable to journals or other shafts.

What I claim is—

1. The improved brass, or journal-bearing, having pendent lateral wings which are provided on their inner sides and at their rear ends with one or more ribs that extend downward, as and for the purpose specified. 105

2. A combined journal-bearing and cap or hood having a pendent front portion and sides, which latter diverge from the portion in contact with the journal, and are provided near their rear ends with transverse ribs that extend downward from a point where they are in frictional contact with the journal, as shown and described. 110

3. The combination, with a journal, a lubricant-holder, or oil-box, and means for transferring lubricant from the latter to said journal, of the journal-cap, having a pendent end and sides, or wings, which latter fit within the oil-box and are provided with guards or deflectors composed of ribs arranged vertically on their inner sides, substantially as shown and described. 115

4. A brass or journal-bearing having its ends beveled, or cut back on an incline, substantially as shown and described. 120

5. The combination, with an axle-journal having a shoulder, of a brass or bearing having its end portion beveled, the extremity of the bevel being practically the same or else 125 130

of less height than said shoulder, substantially as shown and described for the purpose specified.

6. The brass or journal-bearing, having its end portion cut back or beveled, as specified, and having sides, or wings, whose rear ends are cut away and thus recede from the extremities of the bevels, as shown and described for the purpose specified.

10 7. The combination, with the axle box and

journal, of the journal-cap having integral sides and oil-guards, and ends cut away as specified, an oil-box, oil-take-up rollers arranged in the latter, and a spring supporting said oil-box, as shown and described.
